CLAIM

I claim the ornamental design for a cooler riser, as shown and described.

DESCRIPTION

FIG. 1 is a top perspective view of a cooler riser, showing my new design;

FIG. 2 is a bottom perspective view;

FIG. 3 is a top plan view thereof;

FIG. 4 is a bottom plan view thereof;

FIG. 5 is a left side elevation view thereof;

FIG. 6 is a right-side view thereof;

FIG. 7 is a front plan view thereof; and,

FIG. 8 is a rear plan view thereof.

The broken lines show portions of the cooler riser that form no part of the claimed design.
